UNITED STATES PATENT OFFICE

152,160

DESIGN FOR A GAME TABLE TOP

Joseph Klotz, Chicago, Ill., assignor to Mason-Williams Company, Chicago, Ill., a corporation of Illinois

Application June 21, 1947, Serial No. 139,858

Term of patent 14 years

(Cl. D33—14)

To all whom it may concern:

Be it known that I, Joseph Klotz, a citizen of the United States, residing at Chicago, in the county of Cook and State of Illinois, have invented a new, original, and ornamental Design for a Game Table Top, of which the following is a specification, reference being had to the accompanying drawing, forming a part thereof.

I claim:

The ornamental design for a game table top, as shown.

JOSEPH KLOTZ.
